UNITED STATES PATENT OFFICE.

CHARLES H. CARTER, OF BROOKLYN, NEW YORK.

CONTROLLING DEVICE FOR MECHANICAL MOVEMENTS.

961,842.

Specification of Letters Patent. Patented June 21, 1910.

Application filed April 28, 1905. Serial No. 257,882.

To all whom it may concern:

Be it known that I, CHARLES H. CARTER, a citizen of the United States, and resident of Brooklyn, in the county of Kings and State 5 of New York, have invented certain new and useful Improvements in Controlling Devices for Mechanical Movements, of which the following is a specification.

This invention relates to controlling devices for mechanical movements, and particularly to means for controlling the movements of switch-blades or bars useful in various relations and arts.

Among the objects of my invention may 10 be noted the following: to provide a controller for switches whereby the movements of the switch-blade or bar will be limited to the functional area and directed with certainty therein; to provide a controlling 15 means whereby the switch-blade or bar can be operated by successive movements in the same general direction and be caused to assume a new functional position for each successive movement; to provide a switch-controlling device by means of which the 20 switch-blade or bar can be caused to assume different functional positions by successive pulls thereon in the same general direction; to provide a switch-mechanism comprised of 25 certain simple units which are capable of indefinite increase for multiple structures and are susceptible of control, irrespective of 30 number, by a single operating device; and to provide a controlling mechanism by 35 means of which the several functional positions of a switch can be produced in succession without any change in the direction of application of power.

With the above objects in view, and others 40 which will be detailed during the course of this description, my invention consists in the parts, elements and combinations of elements and devices hereinafter described and claimed.

45 In the drawings forming part of this description: Figure 1 is a plan view of a simple device which I have chosen to illustrate the principle of my invention; and Fig. 2 is a section on the line 2—2, Fig. 1.

50 Primarily, it should be understood that the structure shown in the drawings is but one form which I have chosen to illustrate the general principle of my invention and is not to be construed as a limitation, and in 55 the description wherever reference is made

to a specific application of the invention to any given system or art, it is to be understood as explanatory of the general principles and not as a limitation.

Referring to the drawings, the numeral 1 indicates a resilient, reciprocatory, switch-bar or blade, in this instance of my invention pivoted or hinged at *a*, upon a base of suitable material so as to swing or oscillate in the arc of a circle under control in every 60 movement. The base may be of electrical insulating material, and the bar 1 may or may not carry current according to its use. A reciprocatory bar 6 is likewise pivoted or hinged at *b* adjacent the bar 1 and connected to the latter by the link 9, pivoted to each of said bars so that the latter may move together, said link being of insulating material, if in an electrical system, to prevent short-circuiting. The bars are swung 65 upon their pivots, in one direction, by means of the single pull-string 2, or other equivalent device, guided and directed, if desired, by the guide-eye *c*, fixed to the base or other adjacent support, said string being suitably 70 connected at *x*, to said link 9. Return movement is given to said bars, when released, by the spring 3, connected at one end to said link 9 and at its other to said base or adjacent support. The movement of said bars 75 is limited in one direction by means of the stop-pin 8, projecting from the base, and in the opposite direction by the stop-pin 8^a, also projecting from the base. These two stops prescribe the extremes of movement 80 of the two switch-bars and constitute the boundary of the functional area of operation of said bars. Within this functional 85 area is located a combined guide and catch 90 4, and, if in an electric system, said catch will also be a current contact or terminal, and an additional terminal contact 7 may be located in this functional area for two pole-switch circuits.

The catch-contact 4, in this embodiment 100 of my invention, consists of the substantially U-shaped device, arranged horizontally and with its closed end toward the contact 7. The upper prong or guide arm 4^a of the catch is bent, or convexed, so as to depress its end toward the base and form a cam, or guiding device, and its lower guide arm or prong 4^b is bent so as to depress its end substantially into engagement with the base so as to form another cam or guiding 105 110

device. Coöperating with said catch 4, at its open end, is the shunt-guide, having its guiding device or arm 5 bent so as to be elevated from the base, to be slightly convexed so as to be substantially in contact with the end of arm 4^a of the catch, and to have its outer end substantially in contact with the arm 4^b. The guide or arm 5 is secured by its shank 5^a to the base in any suitable manner, and the catch-contact or catch 4 and terminal 7 are secured to the base in any suitable manner, it being understood that, in an electric system, the catch-contact 4, device 7, and switch-bars are current terminals, as presently described.

Each of the bars 1 and 6 is made resilient, as by making it of spring-metal; the terminal contact 7 and shunt-guide 5, may be made of spring-metal, if desired; and the catch-contact is made of spring-metal, though the arm 4^a need not be resilient if the shunt-guide is. Of course, if the controlling device is used in an electric system, the switch-blades and terminals will be composed of conducting material, and the shunt-guide may or may not be, as desired.

Having thus described the details of one form of my invention which I have chosen to illustrate the principles of the latter, the mode of operation, with particular reference to an electric circuit which is to be made and broken, will be understood from the following: Now, with reference to one of the units of the switch-mechanism and controller, assuming it is desired to switch in the current, the cord, or equivalent device will be pulled to the left, viewing Fig. 1, which will cause the bar 1 to flex and run along under the guide arm 4^b, which in turn will flex and allow said arm to pass and assume the position indicated by 1^a, Figs. 1 and 2, this being the extreme of movement to the left which brings said bar 1 into engagement with the stop 8^a. The cord now being released, the spring 3 will assume control and retract said bar 1, so as to draw it into the dotted-line position indicated at 1^b, said bar 1 being in the loop of the catch. It will now be seen that the location of shunt-guide 5 is such that switch-bar 1 cannot slide under said shunt-guide, but must ride over the top thereof and under the arm 4^a of the catch. Another pull in the same direction,—to the left,—will draw the switch-bar 1 into the dotted-line position indicated at 1^c, the movement of said bar being again to the stop 8^a or to the limit of the functional area on the left, whereupon, when the said string is released, the spring will again control, and the resiliency of the bar 1 will enable it to flex and ride over the top of the guide arm 4^a of the catch, and engage the stop 8, which is the other extreme of the functional area of operation of the switch-bar, said stop 8 holding said bar in the full-line position indi-

cated in Fig. 1. Assuming, now, a double-pole switch system, another unit may be coupled with the one just described, without changing the mode of operation or control of the first unit in any respect; that is to say, within the same functional area the bar 6 and contact 7 are located, the bar 6 being coupled to bar 1 by the insulated link 9. A pull to the left on the cord carries the bar 6 over to position 1^d in unison with bar 1 to position 1^a, and release of said cord allows the spring to carry bar 6 into engagement with terminal 7, in unison with movement of bar 1 into the loop of the catch, the latter thus also holding bar 6 in operative position. Another pull to the left on the cord causes the bar 6 to move to position 1^d again in unison with movement of bar 1 to position 1^e, the release of the cord causing spring 3 to draw the bar 6 against stop 8, the bar 6 thus being the means for holding bar 1 in an inoperative position. This simple illustration of the form disclosing the principle of my invention will enable anyone skilled in the art to understand how the units of the mechanism may be multiplied at liberty; that is to say, with a single-pole switch in the circuit the switch-bar 1, catch-contact 4 and shunt-guide 5, with stops 8 and 8^a on opposite sides, would constitute the unit of my switch, while in a double-pole circuit, to such unit would be added the switch-bar 6, contact 7 and link 9 connecting the two bars 1 and 6. In either a single-pole switch circuit consisting of the elements forming the unit just described, or in a double-pole switch circuit containing the elements just described as forming the double unit, the respective units, singly or combined, or the elements thereof can be multiplied to any extent found necessary for any given number or character of circuits without changing either the construction, mode of operation, or the uni-directional character of the pull to operate the same within the functional area prescribed by the stops 8 and 8^a.

From the above description and mode of operation, it will be seen that the following, in addition to those already incidentally noted, are among the advantages of my invention: A switch-mechanism is provided which is controlled by a device adapted to be pulled in a single direction, and for each and every pull in the same direction, a different result or function is secured; a switch-mechanism is produced having a few simple elements which may be increased indefinitely, one or more of them, in order to adapt said mechanism to control a plurality of circuits, or duplicate its functions, without changing its mode of operation or structure in any material or essential particular; a switch-mechanism is produced which can be applied so as to control a plurality of direct circuits either simultaneously or in succession; a con-

trolling mechanism for mechanical movements is produced which is simple, compact, cheap to manufacture, certain and effective in operation, and not liable to get out of order; a controlling mechanism for mechanical movements is provided which operates in a certain prescribed functional area, within which latter it has all its movements and for every movement secures a different result; 5 and a controlling mechanism is provided in which there are certain functional units, which can be indefinitely multiplied without change in mode of operation, coöperative interaction, functional result, or mechanical 10 structure.

Having thus described my invention, what I claim and desire to secure by Letters Patent is:

1. A switch mechanism having in combination a switch-bar; means pivotally supporting said bar at one end; means whereby said bar may be reciprocated on its pivot; means for limiting the reciprocatory movements of said bar in both directions so as to 20 prescribe the movements of the latter; and means, coöperating with said bar at its free end, located within the limits of action of said bar and in the path of movement thereof, for positively holding the same in a functional 25 position, said means including a fixed catch provided with a movable member having means enabling it to yield under pressure so as to cause the bar to be lifted from said 30 functional position.

35 2. A switch-mechanism having in combination a switch-bar; means whereby said bar may be reciprocated; and a device, including a yielding catch, coöperating with said bar during, and between the limits of, its recip- 40 rocations, for causing it to be moved into a different plane of operation and functional position for each movement of said bar in the same direction.

45 3. A switch-mechanism having in combination, a reciprocatory switch-bar; means, coöperating with said bar, normally tending to hold the same in and return it to a given position; means for prescribing the functional area of movement of said bar; and 50 means, including a yielding catch, within said functional area and in the path of movement of said bar for positively holding said bar in a functional position, said catch having means whereby, when said switch-bar is 55 moved, the latter will be released from the catch.

60 4. In combination, an oscillatory switch-bar; means prescribing the functional area of movement of said bar; means within said area for holding said bar in a functional position; a manipulating device connected directly with said bar; said holding means including a yielding catch and a guide by which said bar may be moved through differ- 65 ent planes into different functional positions

by power applied to said manipulating device successively in the same direction.

5. In combination, a plurality of switch-bars; insulating connecting means for said bars, whereby they may move in unison; 70 means for limiting the movements of said bars; and means located in the path of movement of one of said bars for holding both bars in a functional position within the limits of their movements.

75 6. In combination, a reciprocatory resilient switch-bar; means for actuating said switch-bar and for holding it under tension; and a substantially U-shaped catch located in the path of movement of said switch-bar and 80 arranged relatively to the latter so that the closed end thereof will positively hold said switch-bar when the latter is moved in one direction and prevent it from returning to its normal position and the open end thereof 85 will enable said switch-bar to pass from the catch and be moved to its normal position.

7. In combination, a resilient switch-bar, means for actuating said bar; and a catch, coöperating with said bar, having a substantially 90 U-shaped holding portion and a resilient deflecting portion extending within the holding portion.

8. In combination, a resilient switch-bar; means for actuating said bar, a catch, co- 95 operating with said bar, having a holding portion, and a guide coöperating with said catch to flex said bar.

9. In combination, a resilient switch-bar; means for actuating said bar; a catch, co- 100 operating with said bar; having an arm for deflecting the latter, when moved in one direction, into a position such that it may be detained by said catch when moved in the opposite direction; and means coöperating 105 with the catch and for guiding said bar for releasing the latter when again moved in the first direction.

10. A switch-mechanism having a vibratory blade; a device having a fixed position 110 and provided with projecting members forming guides for said blade; an intermediary member extending in a direction across said guides; and means for moving said blade successively between said guides and 115 intermediary member; one of said parts having inherent flexibility and the locking and releasing of said blade being accomplished by flexing said part.

11. In a switch-mechanism, in combination, 120 a blade; means for operating said blade; and a plurality of guiding devices having a fixed position and provided with means adapted successively to guide said blade from its initial, open position, under one of said guiding devices to a second guiding device and under the latter to a closed position, over said last-named guiding device, and to and over a third guiding device to its initial position; one of said parts having inherent 125 130

flexibility and the locking and releasing of said blade being accomplished by flexing said part.

12. A locking device having an oscillatory member; a series of guiding devices having means combined and positioned in relation to said member so that as the latter is oscillated the movement thereof will be successively under and over the first of said guiding devices to an intermediate position between two of them, and from said position by a further oscillation the movement thereof will be successively between two of them and over the succeeding guiding devices of said series to its initial position; one of said parts having inherent flexibility and the locking and releasing of said blade being accomplished by flexing said part.

13. In a switch-mechanism, in combination, a blade; means for operating said blade; a pair of guiding devices having a fixed position and arranged one above the other; and an intermediate guiding device; said devices being combined and operating so as to successively guide said blade from its initial, open position, under one of said pair of guiding devices, under said intermediate guiding device to a closed position between said pair of devices, and from said closed position over said intermediate guiding device, and over the other of said pair of guiding devices, to its initial position; one of said parts having inherent flexibility and the locking and releasing of said blade being accomplished by flexing said part.

14. In a device for controlling mechanical movement, the combination with a moving member, of a device having a fixed position and provided with a plurality of projections forming substantially parallel guides for said moving member, an intermediary member acting in conjunction with said device and moving members having means to alternately lock and release the latter when it is successively moved in one direction one of said parts having inherent flexibility and the locking and releasing of said member being produced by flexing said part; and means for actuating said moving member.

15. A device for controlling mechanical movement having in combination, a moving member; a fixed device having an upper and lower projection; an intermediary flexible member acting in conjunction with said projections to form a guide which shall cause said moving member to be alternately held and released by said device as said moving member is actuated in conjunction with said guide; and means for actuating said member.

16. A device for controlling mechanical movement having in combination, a moving member; a fixed flexible device having an upper and lower projection; an intermediary flexible member acting in conjunction

with said projections to form a guide; and means, for actuating said moving member, which by successive unidirectional pulls will cause the latter to coöperate with said device and intermediary member and move successively under said lower projection into engagement with said device, away from said device over said intermediary member, and over said upper projection to its free position; and the locking and releasing of said member being produced by flexing said device and intermediary member.

17. In a device for controlling mechanical movement, the combination with a moving member; of a fixed device having a pair of substantially parallel projections; an intermediary member extending in the opposite direction between said projections and operating in conjunction therewith to form a guide for said moving member, causing the same to be alternately locked and released as it is moved successively under and over said intermediary member and between said projections; the movable member having inherent flexibility and the locking and releasing of said member being produced by flexing the same.

18. A switch-mechanism having a resilient blade; a device, coöoperating therewith, having means whereby it is adapted to alternately lock and release said blade when the same is, by a succession of movements, shifted in the same direction, said device having projecting members; and an intermediary member coöperating with said projecting members; the several members thus forming a series of guides; and means for moving said blade into coöperation with said series of guides, so that the same will alternately be locked and released.

19. A switch-mechanism having in combination a switch-bar; means, whereby said bar may be reciprocated, including a device for moving said bar into a functional position; a yielding catch coöoperating with said bar; and means whereby said device may be moved universally and the actuation of said device in any direction will cause said bar to be moved into a different position and into and out of engagement with said catch, substantially as described.

20. A controller-catch comprising a supporting shank having a flexible, U-shaped member, and an intermediate member extending between and being overlapped by the free ends of the arms of the U-shaped member.

21. A controller-catch comprising a supporting shank having a flexible, U-shaped member, and a coöoperating member, supported independently of the first member, arranged at an angle to the U-shaped member and extending across the opening of the latter at its free ends.

22. A controller-catch comprising a shank,

and a flexible, U-shaped member offset therefrom, the arms of said member being bent so as to extend in substantially the same direction, and an independently supported coöperating member extending between the arms of said member.

23. A controller-catch comprising in combination a U-shaped member, the arms of which are resilient, and an independently supported coöperating guide the arm of

which extends at an angle to the U-shaped member and across the opening of the latter at its free ends.

Signed at New York in the county of New York and State of New York this 24th day ¹⁵ of April A. D. 1905.
